UNITED STATES PATENT OFFICE.

SAMUEL M. VAUCLAIN, OF PHILADELPHIA, PENNSYLVANIA, ASSIGNOR TO
BURNHAM, WILLIAMS & COMPANY, OF PHILADELPHIA, PENNSYLVANIA,
A FIRM.

LOCOMOTIVE.

No. 844,978.

Specification of Letters Patent.

Patented Feb. 19, 1907.

Application filed April 25, 1906. Serial No. 313,647.

To all whom it may concern:

Be it known that I, SAMUEL M. VAUCLAIN, a citizen of the United States, residing in Philadelphia, Pennsylvania, have invented 5 certain improvements in Locomotives, of which the following is a specification.

My invention relates to that class of locomotives known as "articulated" or "double-frame" locomotives, in which there are two frames, one situated in advance of the other, the two frames being pivoted together, so that while there is a long wheel-base the locomotive can pass around comparatively sharp curves. In this type of locomotive 15 the boiler is carried by one frame and overhangs the other and there is a pair of cylinders carried by each frame. In the present instance the locomotive is of the compound type, the high-pressure cylinders being carried by the frame to which the boiler is rigidly secured, while the low-pressure cylinders are carried by the other frame. A locomotive 20 of this type has a large boiler capacity, a long wheel-base, and yet can be used on roads having comparatively sharp curves.

The object of my present invention relates to the means of pivoting one frame of the locomotive to the other. Heretofore in locomotives of this type the frames turned on a rigid pivot, so that in some instances, especially turning from a straight track to a curve or turning an S-curve, the side friction of the wheels against the tracks was excessive and strained the locomotive considerably. 35 By my invention I make a yielding pivot, so that when the locomotive takes the curve the pivot will accommodate itself to the position of the frames, enabling the locomotive to take the curves more readily and with less friction than heretofore.

In the accompanying drawings, Figure 1 is a side view of a locomotive illustrating my invention, the frames of the locomotive being in full lines and the boiler and cab in dotted lines. The wheels at one side have been removed to more clearly illustrate the invention. Fig. 2 is an enlarged side view, showing the connection between the two frames. Fig. 3 is a sectional plan view on the line 3-3, Fig. 2. Fig. 4 is a vertical sectional view on the line 4-4, Fig. 2; and Fig. 5 is a view of a modification.

A is the rear frame, in the present instance carrying the high-pressure cylinder C, the

boiler B, and the can B'. This frame has the 55 usual axles a a, on which the wheels a' are mounted.

D is a frame situated in advance of the frame A and pivoted thereto in the manner described hereinafter, and this frame carries 60 the low-pressure cylinder C' and supports d d for the overhanging portion of the boiler B and axles d', on which are mounted the wheels d'.

Heretofore the two frames were pivoted 65 together at e e by an ordinary pivot.

Referring now to Figs. 2, 3, and 4, the frame A has extensions A' and A'', and mounted in bearings a² a² is a pivot-pin e, and mounted in bearings a³ a³ in the lower extension A'' is a pivot-pin e'. Projecting from the frame D is an arm D', which is mounted in the space between the two bearings a² a² of the extension A' of the frame A, and projecting from the frame D is an arm D'', extending 70 into the space between the bearings a³ a³ of the extension A'', as clearly illustrated in Fig. 4. In the arm D' is an elongated slot d³, and arranged to slide in this slot is a block E, through which passes the pivot-pin e. The 80 pivot-pin e is held in place by a strap e², Fig. 4. Mounted in the slot d³ in the extension D'' is a block E', through which the pivot-pin e' passes, so that while the two frames are pivoted together the extensions D' D'' are arranged to have a limited sliding motion on the blocks carried by the pivot-pins, that when turning curves the strain is taken off the wheels and side frames. Mounted between the end of the arm D' and a plate f secured to the extension A is a pressure-spring F. This pressure-spring is held between two heads f' in the present instance, extensions on the heads being mounted in sockets 85 in a plate and in the arm, so that the spring 90 will swing with the arm D'. A like spring F' is mounted between the end of the arm D'' and the extension A'', as clearly shown in Fig. 2.

I mount springs I I' between each side of the arm D' and the extension A'. In the present instance the springs are carried by flanged heads i i'. Each head i has a projection which rests in a socket in the arm D', and each head i' has a projection resting in a socket in a screw-plug i², adjustable in the extension A'. i³ i² are jam-nuts for locking the screw-plugs after adjustment. These springs are only mounted between the arm D'

and the extension A', although they may also be duplicated between the arm D' and the extension A'. One of these springs is compressed when the arm moves from the center, while the other spring expands, the tendency of the springs being to keep the arm in a central position and when the frames are on a straight track to tend to keep the two frames in alinement.

10. In some instances the springs may be mounted, as shown in Fig. 5, between the box E and the arm D', the slot in the arm in this instance being elongated for the reception of the springs.

15. The springs may be tension-springs instead of compression-springs and secured to the arm D' and to the extension A' when desired.

Thus it will be seen that by my improvement I relieve the frame and wheels of considerable strain when passing onto or off a curve or passing around a double curve by allowing a certain amount of lost motion at the pivot-point.

25. I claim—

1. The combination in a locomotive of two frames, one in advance of the other, wheels carried by each frame, a rigid extension on one frame and a rigid arm on the other frame, a pivot-pin connecting the two parts, said pivot-pin being rigidly connected to one part and yieldingly connected to the other to allow a limited movement of one frame in respect to the other, substantially as described.

30. 2. The combination in a locomotive of two frames, one mounted in advance of the other, each frame carrying wheels, an extension on one frame, an arm on the other, a pivot-pin carried by one part, the other part being so shaped as to allow for a certain amount of lost motion between it and the pin, and side springs mounted between the extension and the arm, substantially as described.

35. 3. The combination in a locomotive, of

two frames, one frame having two extensions, bearings in each extension, a pivot-pin carried by the bearings of each extension, the other frame having two arms, one arm projecting between the bearings of one extension and the other arm projecting between the bearings of the other extension, blocks carried by the pins, the said arms being slotted to receive the blocks, the slots being elongated so as to allow a limited lateral movement of the blocks in the arms, substantially as described.

4. The combination in a locomotive, of two frames, one mounted in advance of the other, one frame having two extensions one below the other, bearings in each extension and a pivot-pin mounted in the upper extension, a pivot-pin mounted in the lower extension, a block carried by each pivot-pin, two arms projecting from the other frame and one arm mounted above the other, one arm having an elongated slot to receive the upper block and the other arm having an elongated slot to receive the lower block, and springs mounted between the sides of the upper arm and the upper extension, substantially as described.

5. The combination in a locomotive, of two frames, one mounted in advance of the other, an extension on one frame, a pivot-pin carried by said extension, an arm on the other frame having an elongated slot, a block mounted on the pivot-pin and mounted in the slot, adjustable plugs mounted in each side of the extension, springs mounted between each plug and the arm, and a spring mounted between the end of the arm and the plate secured to the extension, substantially as described.

In testimony whereof I have signed my name to this specification in the presence of two subscribing witnesses.

SAMUEL M. VAUCLAIN.
